(57) **CLAIM**

The ornamental design for a solar cell for artificial satellite, as shown and described.

DESCRIPTION

FIG. 1 is a front view of a solar cell for artificial satellite showing the first embodiment our new design;

FIG. 2 is a rear view thereof;

FIG. 3 is a top view thereof;

FIG. 4 is a bottom view thereof;

FIG. 5 is a left side view thereof;

FIG. 6 is a partially enlarged view taken along line 6-6 of FIG. 1;

FIG. 7 is an enlarged cross-sectional view taken along line 7-7 of FIG. 6;

FIG. 8 is a front view of a solar cell for artificial satellite showing the second embodiment our new design;

FIG. 9 is a rear view thereof;

FIG. 10 is a top view thereof;

FIG. 11 is a bottom view thereof;

FIG. 12 is a left side view thereof;

FIG. 13 is a partially enlarged view taken along line 13-13 of FIG. 8;

FIG. 14 is an enlarged cross-sectional view taken along line 14-14 of FIG. 13;

FIG. 15 is a front view of a solar cell for artificial satellite showing the third embodiment our new design;

FIG. 16 is a rear view thereof;

FIG. 17 is a top view thereof;

FIG. 18 is a bottom view thereof;

FIG. 19 is a left side view thereof;

FIG. 20 is a partially enlarged view taken along line 20-20 of FIG. 15; and,

FIG. 21 is an enlarged cross-sectional view taken along line 21-21 of FIG. 20.

The parts shown in the broken lines do not form part of the claimed designs. The right side views are omitted because they are symmetrical to the left side views.
